DRINKING CUP

William H. Inman, Newark, N. Y., assignor to
 Bloomer Bros. Company, Newark, N. Y., a corporation of New York

Application June 20, 1933, Serial No. 676,693

4 Claims. (Cl. 215—100)

This invention relates to drinking cups and has for its object the provision of a simple and satisfactory drinking cup which may be attached to the neck of a bottle to assist in drinking liquid from the bottle.

A further object is the provision of a cup which can be made economically by existing machinery at a minimum of expense.

To these and other ends the invention resides in certain improvements and combinations of parts, all as will be hereinafter more fully described, the novel features being pointed out in the claims at the end of the specification.

In the drawing:

Fig. 1 is a front elevation of a cup constructed in accordance with a preferred embodiment of the invention;

Fig. 2 is a side elevation of the same applied to a bottle;

Fig. 3 is a plan of the cup and bottle shown in Fig. 2;

Fig. 4 is a fragmentary vertical section through the bottom portion of the cup illustrating its attachment to the bottle;

Fig. 5 is a plan of a preferred form of blank used for making the cup, and

Fig. 6 is an enlarged diagrammatic section substantially on the line 6—6 of Fig. 5;

The same reference numerals throughout the several views indicate the same parts.

As is well known, it is frequently difficult and inconvenient to drink liquid directly from a bottle. Also it is often expensive or inconvenient for the proprietor of an establishment selling liquid in bottles, to provide glasses into which the liquid may be poured in order to be drunk.

The present invention provides a simple, compact, and inexpensive drinking cup which may be attached to the neck of a bottle after the cap or other bottle closure has been removed, and which facilitates drinking the liquid from the bottle, while at the same time requiring only one hand to hold both the bottle and the cup, leaving the person's other hand free for any other use, as for example holding a sandwich being eaten at the same time.

Referring now to the drawing, which illustrates a cup constructed in accordance with a preferred embodiment of the invention, there is shown a cup made up from suitable sheet material such as cardboard or fiberboard, preferably of fiberboard having a plurality of plies. The cup has a bottom 10 which is preferably flat or substantially flat, and suitable walls rising upwardly from this bottom.

The bottom is provided with an aperture 11 (Figs. 5 and 6) of slightly smaller size or diameter than the groove 12 usually found in the upper portion of the neck 13 of a conventional beverage bottle 14. The bottom 10 is provided immediately around this opening 11 with a resilient portion which may be deformed when a bottle neck is thrust through the opening, so that the edges of the opening will allow the neck to enter the opening and will engage relatively tightly with the bottle neck to provide a substantially liquid tight joint.

One way of forming the edge of the opening which has been found to be extremely satisfactory in use, is to provide it with outwardly extending slits to form a plurality of resilient tongues around the opening. Preferably the slits do not extend all the way through the bottom, but certain slits extend from one side partly through the bottom and other slits extend from the other side partly through the bottom, out of alinement with the first slits.

As before stated, the bottom is preferably constructed of fiberboard having a plurality of plies. It will be readily understood by those familiar with fiberboard that these plies are to some extent interlaced with and bound to each other, but that they nevertheless can be separated by slight force. Fig. 6 indicates diagrammatically one or more upper plies 10^a, and one or more lower plies 10^b, and the line of cleavage 10^c between them. Usually it is preferred to use about four plies in making up the fiberboard employed for manufacturing the drinking cups of the present invention, in which case the line 10^c would indicate diagrammatically the junction between the two middle plies, and the portions 10^a and 10^b would each consist of two plies, but obviously the number may be varied as desired.

The slits 20, shown in full lines in Fig. 5 and indicated diagrammatically in Fig. 6, preferably extend downwardly from the top surface of the bottom member 10 through the plies constituting approximately the upper half of the thickness of the bottom member, and terminate at or slightly below the cleavage plane 10^c. Between and out of alinement with these slits are other slits indicated by the dotted lines 21 in Fig. 5, and shown diagrammatically in Fig. 6, which extend upwardly from the bottom through the plies constituting approximately the bottom half of the member 10, and terminate at or slightly above the cleavage plane 10^c. Thus there are formed in effect two series of tongues which overlap and break joints with each other, and which are

capable of separating from each other along the cleavage plane 10^c so that the tongues of one series may slide on or slip relatively to the tongues of the other series. When a bottle neck is thrust 5 upwardly through the opening 11, the tongues are deformed and curled up to permit entrance of the bottle neck, and then engage resiliently with the groove 12 near the top of the bottle neck, substantially as shown diagrammatically in Fig. 10 4, the resilience of the tongues causing them to press tightly against the bottle neck and the overlapping relation of the two plies or layers of tongues causing them to maintain a substantially liquid tight joint.

15 The bottom 10 of the cup is preferably of polygonal shape and in the form here shown it is substantially square. Suitable walls rise upwardly from the side edges of the bottom, such as the walls 30 which may be designated for convenience 20 as the front and back walls of the cup, and the walls 31 which may be designated for convenience as the side walls. When the cup is made from the blank illustrated in Fig. 5, the side walls 31 may each be formed of two overlapping portions 25 31^a and 31^b glued together and embracing between them a flap 32 attached to the side of the bottom 10 as plainly shown in Fig. 5, thus making a liquid tight joint between the side walls and the front or back walls, and also between all of these 30 walls and the bottom.

As it is frequently inconvenient to drink from a flat plane surface, provision is made in the present cup for readily deforming one or more of the walls out of a plane to make it of a shape more 35 convenient for drinking. For example, the front and back walls 31 may each have score lines 35 extending obliquely upwardly from the lower corners of the wall and meeting at a point intermediate the height of the wall and substantially on 40 the center line thereof, and a score line 36 extending upwardly from this junction substantially along the center line to the upper edge of the side. These score lines 35 and 36 may be either 45 cut scores or embossed scores, though preferably cut scores are employed. When a side 30 is scored as thus indicated, it is readily apparent that the upper portion of it may be deformed to a somewhat V-shape as plainly illustrated in Fig. 3, for example, thus making the upper edge of this wall 50 more convenient to drink from. In addition the upper edge may be made of any desired shape or form in a vertical direction, as for example having a scallop or depression 40 formed therein.

It will be understood that in the preferred embodiment the entire cup is made from a single piece of sheet material such as fiberboard having a plurality of plies, and is formed up from a blank suitably shaped as shown for example in Fig. 5. After being formed up, the walls of the 55 cup are somewhat tapered as indicated in Figs. 1 and 2, so that a series of such cups may be readily nested in each other for convenient shipping.

When the cup is to be used, the cap or other bottle closure is first removed and then the bottle neck is thrust through the bottom of the cup until the bottom engages the groove 12 near the top of the bottle neck, as indicated diagrammatically in Figs. 2 and 4. With the parts in this position, the cup is held tightly on the bottle neck 60 and will maintain its position so that it is not necessary to hold the cup separately but only the bottle need be grasped by one hand. One edge of the cup is then brought to the person's lips and the bottle is tipped until the liquid runs from the 70 bottle into the cup and fills the cup approximate- 75

ly up to the edge with which the lips are engaged. Thus only one hand is needed for drinking the entire contents of the bottle, and the other hand is free for any other desired use, while at the same time drinking is accomplished much more conveniently and expeditiously than when it is attempted to drink directly from the neck of the bottle. Also the cups, being small, can be manufactured comparatively inexpensively, and it will be readily appreciated by those skilled in the art 80 that they may be made by conventional machinery commonly available in the trade and usually found in most well equipped factories engaged in making cartons, pails and the like.

It is to be noted that the walls of the cup extend up to a material distance above the top of the bottle neck. Thus as the liquid flows from the bottle neck, it will not flow against or inconveniently close to the drinker's nose or lips, as might be the case if the bottle neck extended up relatively near to the top of the cup.

While one embodiment of the invention has been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. A drinking cup for attachment to the neck of a bottle, said cup comprising a bottom having an opening through which the neck of a bottle may be thrust, and a plurality of slits extending outwardly from said opening to provide resilient tongues around said opening for close engagement with a bottle neck, said slits extending through only a part of the thickness of said bottom.

2. A drinking cup for attachment to the neck of a bottle, said cup comprising a bottom having an opening through which the neck of a bottle may be thrust, and a plurality of slits extending outwardly from said opening to provide resilient tongues around said opening for close engagement with a bottle neck, certain of said slits extending from one side of said bottom only part way through the thickness of said bottom, and certain others of said slits extending from the opposite side of said bottom only part way through the thickness of said bottom in positions out of alignment with the slits extending from the other side.

3. A drinking cup for attachment to the neck of a bottle, said cup comprising a bottom of fiber board made up of a plurality of plies and having an opening of slightly smaller size than a bottle neck so that a bottle neck may be thrust through said opening by deforming the material of said bottom around said opening, and a plurality of slits in said fiber board extending in a direction outwardly from the edge of said opening, certain of said slits extending from one side of said fiber board through at least one of said plies but not through the entire thickness of said board, and others of said slits extending from the opposite side of said board through at least one of said plies but not through the entire thickness of said board.

4. A drinking cup for attachment to the neck of a bottle, said cup comprising a bottom of fiber board made up of a plurality of plies and having an opening of slightly smaller size than a bottle neck so that a bottle neck may be thrust
